(57) **CLAIM**

The ornamental design for a head for a toy figure, as shown and described.

DESCRIPTION

FIG. 1 is a top, front perspective view of our ornamental design for a head for a toy figure;

FIG. 2 is a front view thereof;

FIG. 3 is a rear view thereof;

FIG. 4 is a right side view thereof;

FIG. 5 is a left side view thereof;

FIG. 6 is a bottom plan view thereof; and,

FIG. 7 is a top plan view thereof.

The broken lines in each of the figures are for environmental purposes only and form no part of the claimed design.

1 Claim, 7 Drawing Sheets
